(57) **CLAIM**

The ornamental design for electronic card reader device with camera and displaying means, as shown and described.

DESCRIPTION

FIG. 1 is a top plan view of the electronic card reader device with camera and displaying means.

FIG. 2 is a bottom plan view of the electronic card reader device with camera and displaying means.

FIG. 3 is a right side elevation view of the electronic card reader device with camera and displaying means.

FIG. 4 is a left side elevation view of the electronic card reader device with camera and displaying means.

FIG. 5 is a front view of the electronic card reader device with camera and displaying means.

FIG. 6 is a rear view of the electronic card reader device with camera and displaying means.

FIG. 7 is a top front left perspective view of the electronic card reader device with camera and displaying means; and,

FIG. 8 is a bottom perspective view of the electronic card reader device with camera and displaying means.
